WINDOW CONSTRUCTION

Edward J. Winship, Baltimore, Md., assignor to
 Pittsburgh Corning Corporation, Allegheny
 County, Pa., a corporation of Pennsylvania

Application September 28, 1938, Serial No. 232,126

4 Claims. (Cl. 20—42)

The present invention relates to window constructions and it has particular relation to constructions comprising a pair of panes or plates of glass arranged in spaced parallel relation in order to provide a dead air space therebetween.

One object of the invention is to provide a double glazed or storm window involving inner and outer swinging sashes which are so interconnected that opening of one simultaneously opens the other.

A second object of the invention is to provide a window of the foregoing type which can readily be so opened as to expose all surfaces for cleaning from the interior of the building.

The lighting, insulation and ventilation of buildings have long presented problems, the simultaneous solution of which was relatively difficult. The common method of admitting light and air has heretofore involved the provision of windows comprising single thickness of glass disposed in sashes which, if desired, could be opened. Such windows were not entirely satisfactory because the rate of heat transfer through the glass was relatively high. During winter months the glass, sometimes, became so chilled by the outside air that condensation of moisture from the relatively warm air within the building occurred. This latter phenomenon was substantially accentuated by the introduction of air conditioning in which moisture was introduced into the air within the room to raise the relative humidity to the optimum value for the occupants.

In order to reduce heat losses through the windows and also to prevent chilling of the inner surface of the glass to such extent as to cause condensation of moisture upon the surface thereof it has been proposed to provide windows comprising two sheets or plates of glass so spaced as to provide a dead air chamber therebetween. The chamber of course acts as an insulator to prevent excessive transmission of heat and the chilling of the inner glass. This type of construction was, however, found to be objectionable for certain reasons. For example, moisture was present in the space between the plates of glass and often would condense upon the inner surface of the outer sheet where it tended to obscure vision and also caused deterioration of the glass to such degree as to impair the clarity and polish of the latter. In the conventional doubly glazed construction it was difficult to obtain access to all surfaces of the glass in order to clean the latter, and likewise opening of both the inner and outer sashes, in order to admit air directly

from the outside atmosphere into the room, was difficult.

Relatively recently, it has been proposed to form the walls of buildings of hollow blocks of glass. These admitted light and by reason of the dead air spaces therewithin, they also provided a high degree of heat insulation. Likewise, the tendency of moisture to condense upon the walls was reduced or overcome. However, vision through conventional glass blocks is obscured if not entirely prevented, so that walls thereof create in many persons a feeling of imprisonment. Moreover, provision for the direct admission of outside air, when desired, offers difficulty.

The present invention contemplates the provision of a storm sash structure which is excellently adapted for use in walls of glass blocks. In this construction inner and outer sashes are so mounted in a frame that they can readily be swung into a position admitting of free access to all sides of both sheets of glass, even from the interior of the room or building and in which the two sashes are interconnected by means admitting of simultaneous opening thereof for purposes of ventilating the room or building in which they are employed.

For a better understanding of the invention reference may now be had to the accompanying drawing in which Figure 1 is a diagrammatical view illustrating the movement of the sashes embodied in the invention.

Figure 2 is a fragmentary cross-sectional view of a portion of the jamb of the window.

Figure 3 is a fragmentary cross-sectional view through the bottom portion of the construction.

Figure 4 is a fragmentary cross-sectional view showing the connection between the sash operating mechanism and the sashes.

Figure 5 is a detailed view of a spring device employed to lock the connecting device disclosed in Figure 4 in desired position with respect to the sash to which it is connected.

Figure 6 is a detailed cross-sectional view of a hinged connection for securing the sashes disclosed in Figure 1 in the frame.

Figure 7 is a cross-sectional view illustrating a further application of the invention.

In the drawings like numerals refer to like parts throughout.

In the form of the invention shown in Figures 1 to 6 inclusive the window frame 10 comprising a bottom portion 11, jambs 12 and a head 13 comprises, as shown in Figs. 2 and 3, wooden sides 14 and 15. These sides at their inner edges con-

tact with the web portions 17 of members 18 of T cross-section having flanged portions 19. The entire frame assembly is maintained by means of bolts 21 extending through holes in members 14 and 15 and webs 17 and having nuts 22 threaded thereupon.

As best shown in Figure 2 the jambs 12 are provided along their inner and outer edges with channels 23, which preferably comprise separate members of metal secured to the jambs by convenient means such as screws 24. It will be apparent that these members need only extend to the mid portion of the jambs.

A pair of spaced sashes 26 and 27 are connected for combined pivotal and sliding movement in the channels 23 by means including slides 28 (shown in detail in Fig. 6) disposed in the channels. These slides are provided with tubular bosses 29 upon which is pivoted a sleeve 31 having a flange or lug 32 secured to the sides of the sashes 26 and 27 respectively at the lower and upper corners thereof. In order to retard movement of the slides 28 in the channels 23 a pointed plug 33 is disposed in the boss 29 and is urged into depressions in the bottom portions of the channels by means of a coiled spring 34, which at its rear extremity abuts against a plug 36 threaded into the sleeve 31.

Sashes 26 and 27 are interconnected for simultaneous actuation upon the pivots by means comprising a lever 37 hinged at its mid portion to the inner face of one of the jambs 12, by means of a pin or pivot 38, which at its inner end may be threaded into the member 18. At its outer end, the screw extends through a strip 39, disposed parallel to jamb 12. At its opposite ends the lever is pivoted within yokes 40 and may be attached to or integrally formed with a slide member 41. This slide is mounted for movement within guides or channels 42, preferably formed of metal and secured in suitable grooves in the inner faces of the sashes by means of screws 45.

For purposes of locking the slide 41 in any desired position of adjustment along the guides 42, the edges of the latter are provided at suitable intervals with notches 46 adapted to receive arcuate end portions 47 of a spring plate 48 (best shown in Figs. 4 and 5). This plate is secured to the slide 41 by means of a screw 49.

A seal is provided about the edges of the sashes 26 and 27 when they are in closed position, by means of weather strips 51 comprising strips of thin relatively resilient metal such as brass, steel, or the like. These strips are longitudinally bent to fit within grooves 52 formed in the frame portions 14 and 15, and the marginal portions are inwardly bent in such manner as to provide spring portions 53 and 54, which respectively engage the inner corner and the adjacent edge of the sash frame.

If desired, the construction may be provided with an insect screen 56 which may conveniently comprise a marginal frame 57 of sheet metal resiliently bent as indicated at 58 to grip the edge portions of the wire fabric 59. The frame is also laterally bent to provide a lateral lip portion 61 which is adapted to engage the inner margins of the frame 10. Outward displacement of the frame is prevented by means of stop pins 62 shown in Figure 3 and in order releasably to secure the frame from inward displacement latches comprising balls 63 disposed in opening 64 in the flanges 19 are provided. These balls are resiliently mounted in position by means of helical

springs 66 disposed in opening 64 and engaging at their lower ends with the frame portions 14.

The mode of operation of the construction described is relatively simple. Assuming that the sashes are in the closed position indicated in Figures 2 and 3, and it is desired partially to open them in order to admit air to the building in which the construction is installed, the operator swings the upper edge of the inner sash 26 downwardly, for example to the position indicated in full line in Figure 1. Obviously, as the sash is swung downwardly about its pivot at the lower corner thereof the slide 41 also moves downwardly along the guide 42 and the opposite end of lever 37 swings upwardly to actuate the slide 28 in the sash 27 and thus to swing the lower edge of the latter outwardly about the pivots, at the upper corners thereof. The sashes may be secured in any desired position of adjustment simply by the engagement of the portions 47 of spring plate 48 with the notches 46.

In event that it is desired to swing the sashes to the horizontal positions indicated in dotted line in Figure 1 the downward pressure upon the end of the sash 26 is continued to elevate the lower end thereof and to cause the slide 28 to travel upwardly in the guides 23. When the horizontal position is reached the lever 37 acts as a stop to limit further movement. If desired, to retain the lower edge of the sash in any predetermined position along the guide 23, it will be apparent that the plug 33 actuated by the spring 34 exerts substantial frictional contact with the bottom of the groove and will thus retain the sash in position until substantial force is exerted thereon to cause further movement. When the sashes are in horizontal position it is an easy matter to remove the screen 56 by pulling inwardly thereupon to overcome the resistance exerted by the balls 63. When the screen is removed both sides of both of the glasses are readily accessible for purposes of washing. In order to close the sashes the operation as described is merely reversed.

It will be apparent that certain features of the invention are susceptible of substantial modification. An example of such modification is shown in Figure 7 of the drawings. In this construction a window frame 70 which may correspond substantially to the frame 10 already described is provided with sashes 71 and 72 pivoted as indicated at 73 to slides 74 mounted in guides corresponding to guides 23 shown in Figure 2. In this construction guides 42 in the sashes are omitted. For purposes of actuating the sashes a lever 76 corresponding to lever 37 is pivoted at its mid portion upon a pin 77 and the swinging extremities thereof are hinged to brackets 81 secured to sashes 71 and 72. Lever 76 and links 79 constitute toggles, operation of one of which causes simultaneous actuation of the other, whereby when one sash, e. g., 71, is opened or closed the other sash 72 is correspondingly actuated. The frame may be provided with a screen 82, portions of which, for purposes of clarity, are shown broken away. This screen substantially corresponds to the screen 56 already described. The operation of this embodiment of the invention substantially corresponds to that described in connection with that form of the invention shown in Figures 1 to 6 inclusive.

The sash constructions shown have been described as being adapted to swing about horizontal pivots. However, it will be apparent that it is also quite possible to mount them for swing-

ing about pivots which are vertically disposed.

The forms of the invention herein shown and described are to be considered as merely illustrative of the invention and numerous modifications 5 may be made therein without departing from the spirit of the invention or the scope of the appended claims.

What I claim is:

1. A storm window construction comprising a 10 frame, a pair of spaced sashes providing a dead air space within the frame, guides formed along opposite sides of the frame, slides disposed in the guides, the slides being pivotally connected to the sashes at the corners thereof and means 15 interconnecting the sashes whereby upon operation of one sash the other is simultaneously and correspondingly operated, said means comprising a lever pivoted at its mid portion to the mid portion of the sides of the frame, and being 20 secured at opposite ends to the sashes by means permitting simultaneous rotation and translation between the ends of the lever and the sashes, the sashes both being movable into approximately 25 the same plane, the plane being at the point of pivoting the lever.

2. A storm window construction comprising a 30 frame, a pair of spaced sashes providing a dead air space within the frame, guides formed along opposite sides of the frame, slides disposed in the guides, the slides being pivotally connected to the sashes at the corners thereof and means 35 interconnecting the sashes whereby upon operation of one sash the other is simultaneously and correspondingly operated, said means comprising a lever hinged intermediate its length to the frame and having sliding connections at its ends to the sashes, the sashes both being mov-

able approximately to the same plane in which plane is disposed the pivot of the lever.

3. A window construction comprising a frame, pairs of parallel spaced guides disposed upon two opposite sides of the frame, slides disposed in the guides, two spaced sashes providing a dead air chamber, each of which is hinged at two transversely opposed corners to the guides, means to lock the slides in the guides in any predetermined position, means simultaneously to 10 operate the sashes comprising a lever hinged at its mid portion to the guides and hinged at its opposite ends to the sashes by means permitting simultaneous rotation and translational movement between the ends and the sashes, the 15 sashes both being movable approximately to the same plane in which plane is disposed the pivot of the lever.

4. A window construction comprising a frame, the frame being formed of spaced inner and 20 outer sections of wood and an intermediate section of metal which completely separates the spaced sections, means securing the spaced sections to the intermediate section so that the latter are supported by the intermediate section, 25 spaced sashes providing a dead air chamber secured by pivotal connections to the spaced sections without direct contact with the intermediate section and means for simultaneously operating the sashes, comprising a lever pivoted at its mid portion to the intermediate section and being 30 connected at its extremities to the sashes by means permitting relative rotation and translation between the sashes and the extremities of the lever.

EDWARD J. WINSHIP.
